INVENTOR,
Everett W. Swartwout,
BY Henry J. Lucke,
ATTORNEY.

UNITED STATES PATENT OFFICE.

EVERETT W. SWARTWOUT, OF WHITE PLAINS, NEW YORK.

SMOKING PIPE.

Application filed October 30, 1923. Serial No. 671,633.

This invention relates to smoking pipes and is particularly directed to means for securing improved smoking qualities.

Pursuant to the invention, the smoking pipe including the usual bowl having a stem portion and a separable stem portion carrying the mouth piece, is combined with a member for effectually removing nicotine or other moisture or saliva and dust whereby there is afforded a continuously maintained clear passage through the bore of the pipe stem for the smoke developed upon ignition of the tobacco in the bowl.

Pursuant to the more preferred forms of my invention, such removal of the tobacco dust, saliva, nicotine or other moisture and other products of condensation resulting in the use of the pipe in smoking, is effected by means of a member of non-ignitable material such as metal and shaped spirally or of other nonuniplanar configuration whereby such nicotine or other moisture, dust and the like which are developed upon ignition of the tobacco in the bowl and carried upon inhalation by the smoker into the pipe stem, are effectually impeded and retained at distributed locations within the bore of the stem and effectively out of the path of the smoke. In a similar manner, such provision of means, in the event of saliva entering the mouth piece, directs and retains the same at a similar location, out of effective intercept with the smoke passing through the pipe bore.

Such dust and nicotine or other moisture separating means serves also as a means for thoroughly cleansing the bore of the pipe, by manual withdrawal of the spiral means through the bore, as by removal of the separable portion of the stem from the bowl portion of the stem in a separable type of pipe, whereby upon manual withdrawal of the spiral or equivalent member outwardly from the pipe stem, the dust and nicotine or other moisture are transferred exteriorly of the bore.

Further features and objects of the invention will be more fully understood from the following detail description and the accompanying drawings, in which

Fig. 1 is a vertical central sectional view through the bowl and stem of a pipe, of the form in which the stem is separable substantially at its center;

Fig. 2 is a side elevation of a spiral mem-

ber shown combined with the pipe in Fig. 1; Fig. 3 is a sectional elevation on line 3-3 of Fig. 1 on an enlarged scale;

Fig. 4 is a sectional elevation on line 4-4 of Fig. 3;

Fig. 5 is a sectional elevation on line 5-5 of Fig. 4;

Fig. 6 is an end perspective view, on a somewhat enlarged scale, of the removable stem portion, showing a bayonet joint support for the dust and nicotine or other moisture separating member;

Fig. 7 is a detail side elevation of the end portion of the dust and nicotine or other moisture separating member;

Fig. 8 is a side elevation of a modified form of a dust and nicotine or other moisture separating member;

Fig. 9 is a side elevation of modification, i. e., a helically coiled member, on a greatly enlarged scale; and

Fig. 10 is a sectional view on line 10-10 of Fig. 9.

Referring to Figs. 1 to 6, inclusive, the pipe per se may be of any approved or desired form and general construction, and comprising the bowl 11, the stem portion 12, usually permanently secured to the bowl 11, and the separable stem portion 13, at the outer end 14 of which is the mouth piece, either permanently or removably carried thereby. Such separable feature for the stem portions 12, 13 may be provided by means of the reduced stem portion 15 projecting from the inner end of the stem portion 13 and secured by frictional fit within the recess 16 at the outer end of the bowl stem portion 12.

Within the bore 17 of the pipe stem 12-13 is disposed, pursuant to my invention, a twisted or spirally coiled member 18 of aluminum or like sufficiently stiff and preferably non-corrosive material suitable for the purposes desired. Such member 18 is preferably of a length corresponding to the length of the bore 17 from the mouth piece 14 to a location 19 in advance of the center of the bowl 11, in which circumstance the inner end 20 of the member 18 is provided with an enlarged opening 21, see Fig. 2, or slot or equivalent, whereby an enlarged effective free clearance is provided for the draft from the bottom of the bowl 11 into the stem bore 17.

Upon filling the bowl with tobacco, with

the stem and the dust and nicotine or other moisture member assembled, as indicated in Fig. 1, upon inspiration by the smcker, the smoke is drawn through the bottom of the 5 bowl, thence into contact with the member 18, including a considerable portion of the smoke passing through the slotted opening 21, the path of the smoke then continuing about the passage afforded between the various 10 portions of the member 18 and the wall of the bore 17 of the pipe, whereby the smoke is given a more or less centrifugal movement. The condensed nicotine or other moisture resulting from the ignition of the 15 tobacco, gravitates toward the bottom of the bore 17 and will be distributed in time on the bottom of the bore from the bottom of the bowl toward the mouth piece. Such centrifugal movement of the smoke, carrying any dust or other substance foreign to 20 the smoke, is whirled into contact with such condensed nicotine or other moisture and thereby entrapped. Similarly, in the event of saliva entering the opening of the 25 mouth piece 14, is brought toward the bottom of the bore and operates to catch dust and the like.

Such action is enhanced by providing an effective diameter of the member 18 substantially that of the bore 17 of the stem.

Such member 18 is also preferably provided with suitable means for lodging the same within the bore 17 of the pipe stem, as by providing the member 18 with the 25 spaced lugs 22, 23 for retaining the member 18 relative to the reduced stem portion 15. As is indicated in Figs. 3, 4, 5 and 6, the reduced portion 15 may be provided with the correspondingly spaced re-entrant recesses 24, 25, arranged to respectively receive the retaining lugs 22, 23 and forming therewith a bayonet joint, whereby upon withdrawal of the separable stem portion 13, the member 18 is simultaneously withdrawn 40 through the stem portion 12, but retained by the above described support for the member 18 within the removable stem portion 13.

Such withdrawal of the member 18 through the bore of the stem portion 12 effects a displacement of the edge portion of the member 18 longitudinally along and against the wall of the bore and thus producing a scraping action, and removing 55 dust, nicotine or other moisture and the like therefrom. Such withdrawal action may be repeated as often as desired.

Upon disconnecting the member 18 from the separable stem portion 13, and withdrawing the same through the bore thereof, a similar removal action is effected for the dust, nicotine or other moisture from the bore of the stem portion 13.

In Fig. 3, the member 18 is shown lodged 60 with its retaining lugs 22, 23 respectively in

the bayonet slots 24, 25 and the effectual diameter of the spiral member 18 substantially that of the bore 17, that is to say, to make an easy fit therein.

In Fig. 7, the opening 30 at the inner end 70 of the member 18 is shown somewhat enlarged along the length of the member 18.

If desired, and as indicated in Fig. 8, the member 31, corresponding to the aforesaid member 18 may be provided with the openings 32, 32 adjacent the opposite ends of the member 31, whereby the opening 32 located adjacent the opening of the mouth piece 14 when positioned within the pipe, may be employed to receive the end of the 80 match, tooth pick, button hook, bent wire or the like, to afford withdrawal of the member 31 from the bore of the pipe. Such form of the invention may be employed in pipes of the separable stem type, as indicated in Fig. 1, or with pipes having a stem integral throughout its length.

From the above, it will be perceived, as I have discovered from actual use of my invention, substantially all the nicotine, 90 moisture and other water content of the gases resulting from combination of the tobacco, are automatically entrapped and retained within the bore of the pipe while sufficient full passage is provided at all 95 times for the free draft through the pipe bore. The smoking derived by means of a pipe having my invention, is "cool" and without any "bite", and allows such pleasurable smoking for a comparatively long 100 period of use, and particularly for relatively long periods of continuous use.

The invention also provides for ready removal of the nicotine, dust and the like from the bore without the necessity of having any auxiliary device, such as a pipe cleaner, and the cleansing is readily effected without soiling the hands of the user, as the cleaner member may be grasped by a piece of newspaper or cloth or the like and cleansed.

The configuration of the member 18 may be varied, as by twisting a metal strip irregularly, as distinguished from the regular spiral as is illustrated in Figs. 1 and 8, while retaining the essential features of the provision of a whirling path for the smoke through the bore, a plurality of edge or other portions of the body of the member in spaced contact with the walls of the bore and suitability for grasping one end thereof for facilitating its withdrawal from the bore. In Figs. 9 and 10, I have illustrated a helically coiled member 33, and preferably of a triangular or other polygonal cross-section, to provide spaced edge or relatively sharp portions for engagement with the walls of the bore of the pipe stem.

Whereas I have described my invention by reference to specific forms thereof, it will be understood that many changes and modi- 130

fications may be made without departing from the spirit of the invention.

I claim—

The combination of a pipe comprising a bowl portion, a bowl stem portion, a bored mouth piece stem portion and means for disconnectably connecting said mouth piece stem portion with said bowl stem portion, said connecting means comprising a tubular member secured to and projecting from said mouth piece stem portion, said tubular member being provided with a set of bayonet

slots, a spirally arranged member disposed in the bore of said bowl stem portion and the bore of said mouth piece stem portion, 15 said spiral member engaging the walls of said bores at spirally continuous locations, a set of lugs carried by and projecting from said spiral member and removably received within said set of bayonet slots. 20

In testimony whereof I have signed this specification this 26th day of October, 1923.

EVERETT W. SWARTWOUT.
